(57) **CLAIM**

The ornamental design for a novelty gift bag, as shown.

DESCRIPTION

FIG. 1 is a perspective view of the novelty gift bag;

FIG. 2 is back view thereof;

FIG. 3 is a right side view thereof;

FIG. 4 is a front view thereof;

FIG. 5 is a left side view thereof;

FIG. 6 is a top view thereof;

FIG. 7 is a bottom view thereof;

FIG. 8 is a perspective view thereof; and,

FIG. 9 is a vertical cross-section view thereof, the cross-section taken perpendicular to FIG. 3 and depicting the center divider therein.

The broken lines shown in FIGS. 1-9 show environmental structure and form no part of the claimed design.

1 Claim, 4 Drawing Sheets**FIG. 1**

FIG. 2

FIG. 3

FIG. 4

FIG. 8

FIG. 9
